UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

TYPE-WRITING MACHINE.

1,227,438.

Specification of Letters Patent. Patented May 22, 1917.

Application filed December 9, 1916. Serial No. 135,958.

To all whom it may concern:

Be it known that I, EDWARD B. HESS, a citizen of the United States, residing at Brooklyn, in the county of Kings and State 5 of New York, have invented certain new and useful Improvements in Type-Writing Machines, of which the following is a specification.

This invention relates to the mechanism 10 of type-writing machines for effecting changes in the letter case printing and particularly to mechanism of this class in which a key lever is employed for shifting the platen or carriage from lower to upper case position. In such mechanism latches operated by shift keys have heretofore been employed for holding the carriage in both upper and lower case positions and the arrangement has been such that whenever the 20 carriage was lifted to upper case position by a shift key a latch was made to engage the carriage or the shift rail beneath the carriage and thus hold it in its upper position until the shift key was released. In 25 such construction as soon as the shift key was released the latch was also released and therefore the latch was actuated at each operation of the shift key. Said mechanism has also heretofore been provided with locking devices operated by a 30 separate key known as the "shift lock key" which when depressed held the shift key in such manner as to hold the carriage in upper case position.

35 In the operation of the shifting and locking devices as previously constructed the carriage was usually held up by the appropriate latch each time that the shift key was depressed even when it was desired to 40 print only a single capital letter. This is not always necessary. It is often preferable to lift the carriage and hold it momentarily during the printing of a single letter by the shift key only and to bring the holding up 45 latch into operation only when a series of capital letters is to be printed. According to my present invention instead of operating the holding up latch by the shift key I actuate it by the shift lock key, which latter is brought into operation only when 50 it is desired to print a series of capital letters.

In my pending application No. 116,604, filed August 24, 1916, I have shown means 55 interposed between the shift key and the

carriage or the part to be shifted for cushioning the movement of the shift key after the shifting operation is completed, and my present improvements are preferably used in connection with such cushioning devices. 60

In the accompanying drawings I have shown my invention applied to a Royal Standard machine of well known construction.

Figure 1 is a view in longitudinal section 65 of the machine frame or casing and it shows the carriage and the carriage shifting mechanism in side elevation. This figure of the drawing shows the carriage in lower case position.

Fig. 2 is a detail view on an enlarged scale showing the connection between one of the shifting links or rods and the carriage lifting levers.

Fig. 3 is a detail view in section of the 70 cushioning device interposed in the connections between the shift key and the carriage shift levers. This figure of the drawing shows the cushioning device in normal condition when the shift key is in elevated 75 position.

Fig. 4 is a view in side elevation showing the carriage in elevated position and the shifting mechanism in the position it assumes after the carriage has been lifted. 80 This figure of the drawing also shows by dotted lines how an additional cushioned movement is given to the shift key after the carriage is fully raised.

Fig. 5 is a view similar to Fig. 1 but 85 shows the carriage in lifted position as in Fig. 4, and it also shows the condition of the mechanism after the shift lock key has been depressed and the holding up latch 90 has been moved into position to support the carriage.

Fig. 6 is a detail view in section of the cushioning device also shown in Fig. 3, but shows the condition of the parts after the shift key has been depressed in the manner 100 indicated by dotted lines in Fig. 4.

The carriage A supports a platen B and is supported at its front on a shift rail C, which has downwardly extending arms D connected at their lower ends to links E 105 pivoted to the machine frame at e. Levers F are pivotally connected to the arms D near their upper ends and the rear ends of the levers are pivotally connected with the machine frame at f. It will be understood 110

that there is a pair of links E and a pair of levers F, those on one side of the machine only being shown.

- 5 The shift lever H is pivoted at *h* to the machine frame and carries a finger key *h'*. A shift locking lever and key I are associated with the shift key lever in the usual way. Said lever H is in bell crank form and is connected by a rod K with the locking latch G engaging a lug *g'* for holding the carriage in lower case position, and said lever H is connected with one of the levers F by links or rods associated with adjusting and cushioning devices of the kind shown in my application for patent before mentioned. It will be understood that more than one shift lever may be employed. Preferably a single locking lever is used.
- 20 A spring S connected with one of the levers F at *s* and adjustably connected with the machine frame at *s'* is employed for counterbalancing to some extent the weight of the carriage in the usual way.
- 25 The shift lock lever I operates a locking lever J pivoted to the machine frame at *j* and having an end *j'* normally engaging a pin *i* on the shift lock lever I. Said lever J is formed with a recess *j'* and said lever 30 is held in the position shown in Fig. 1 by a spring *j*². When the shift lever H is depressed and the levers I and J are also depressed the parts occupy the position shown in Fig. 5 when, as will be observed, the pin 35 *i'* on the lever H enters the recess *j'* and the case shifting lever is held in depressed position. By merely depressing the shift key *h'* the pin *i'* will be disengaged from the lever J and the spring *j*² will cause the 40 lever J and the shift lock lever to rise, thus releasing the case shift lever which will also rise to normal position. The carriage will then lower and the latch will engage the lug *g'*.
- 45 A rod or link L is connected with the lower end of one of the levers F and another rod M is connected with the bell crank lever H. The connection between the rod L and the lever F is preferably made by 50 forming a loop *a* in the rear end of the rod which engages a pin *f'* on the lever and this loop at its front end is connected with a spring *g* which is attached at its rear end to the pin *f'*. When the carriage is lifted 55 the spring *g* is under tension as indicated in Fig. 5, but when the carriage is lowered the spring causes the rear end of the loop to separate from the pin a short distance so that when the shift lever is again de- 60 pressed there is a little lost motion before the rear end of the loop engages the pin *f'* and thus before the raising operation of the carriage commences. In this way time is given for the latch G to be disengaged from 65 the carriage before the latter commences to

rise. Between the rods L and M the adjusting and cushioning device N is interposed. The rod M is adjustably connected at its front end with a plug *m* screwed into the rear end of a tube *m'* and held in its 70 adjusted position by a nut *m*². The rod L enters an internally threaded sleeve *l* and is adjustable therein, being held in adjusted position by a nut *l*'. The sleeve *l* enters the tube *m'* and is formed at its inner end 75 with a head *l*². Between the head *l*² of the sleeve *l* and the end of the tube *m'* is interposed a spring O placed under compression and tending to move the rod L rearward or to press the tube forward. 80

When the shift key is depressed it at first draws the rods L and M and their connections rearward and raises the carriage to its full extent without putting further compression on the spring, but the shift 85 key may be further depressed, and the spring O put under compression and act as a cushion to the operation of the shift key. When the shift key is released the compression of the spring is relaxed and the parts 90 returned to their normal position in the usual way. Fig. 3 of the drawings shows the condition of the cushioning spring when the carriage is in its lowered position while Fig. 6 shows the condition of the cushioning 95 spring when put under compression. The spring is so adjusted that when the shift key is operated to raise the carriage against its stop T it is not further compressed, but an additional movement given 100 to the shift key will put the spring under compression in the manner before described.

As thus far described the mechanism is of well known construction or is shown in my application for patent above mentioned, 105 but it is often desirable to positively hold the carriage in its lifted position by a latch after the shift key has been depressed. As before stated this has previously been done, but such latch has been operated by the 110 shift key each time that the shift key was depressed. According to my present invention I provide a latch Q pivoted at *q* to the machine frame and adapted to extend under the lug *g'* on one of the arms D, which lug 115 is also engaged by the latch G at the proper time. The latch Q is connected by a link or rod Q' with an arm I² formed on the shift lock lever I. It will be understood 120 that the shift lever H is operated independently of the lock lever I so that the shift key lever may be operated to raise and lower the carriage for upper and lower case printing without operating the holding up latch Q, but when it is desired to print a series 125 of capital letters the shift lock lever is depressed to thus hold the shift key levers in depressed position with the carriage in lifted position and at the same time the holding up latch Q is brought into position to hold 130

the carriage in upper case position in the manner indicated in Fig. 5.

While I have shown my improvements as applied to a Royal Standard machine, and 5 as being used in connection with a shift key having cushioning devices of the kind illustrated, it is understood that my claims are not all limited to the particular mechanism shown and hereinbefore described. Furthermore 10 my invention may be applied to machines of various kinds constructed to effect the shifting from lower case to upper case printing in various ways. One embodiment 15 of my invention is illustrated which is sufficient to indicate the manner in which my invention may be efficiently used.

It will of course be understood that, when it is desired to print a series of capital letters, the shift lock lever I may be depressed 20 without having first depressed the shift key lever as the construction of the mechanism is such that the depression of the lever I will cause the shift lever H to be also depressed and held until it is operated 25 to release the locking mechanism.

I claim as my invention:

1. A case-shifting mechanism for typewriting machines comprising means for moving the part to be shifted to shifted position, cushioning means therefor, means for locking the mechanism in shifted position, a device for rigidly sustaining the shifted part when held by the tension of the cushioning device, and means for moving 35 said locking means for the shift mechanism into and out of operative position.

2. A case-shifting mechanism for typewriting machines comprising means for moving the part to be shifted to shifted position, cushioning means therefor, means for locking the mechanism in shifted position, a device for rigidly sustaining the shifted part when held by the tension of the cushioning device, and means operated by 45 said locking means for the shift mechanism for moving said sustaining device out of operative position.

3. A case-shifting mechanism for typewriting machines comprising a shift key, 50 connections between the shift key and the part to be shifted provided with yielding cushioning devices, a shift key locking device, means for operating it, and means for sustaining the shifted part in shifted position while yieldingly held by said shifting devices.

4. A case-shifting mechanism for typewriting machines comprising a shift key, 55 connections between the shift key and the part to be shifted provided with yielding devices whereby the shifted part is held

yieldingly in its shifted position, a shift key locking device for holding the shift key in shifted position, a lever for operating the shift key locking device, a device for 65 rigidly holding the shifted part in shifted position, and connections between said holding device and the lever which operates the shift key locking device.

5. In a case-shifting mechanism for typewriting machines, a shift key, connections 70 between the shift key and the part to be shifted, a shift key locking device, a key operatively connected therewith, a latch pivotally connected with the main frame and 75 adapted to assume a vertical position to engage the part to be shifted and to support it, and connections between the latch and the shift locking key.

6. In a case-shifting mechanism for typewriting machines the combination of carriage raising mechanism, a shift key lever operatively connected therewith, a locking device for the shift key adapted to depress 80 the shift key lever, a shift lock key for actuating said shift key locking device, a latch 85 engaging the carriage raising mechanism when the latter is elevated, and connections between the latch and the shift lock key for causing it to engage the carriage raising 90 mechanism when the shift lock key is depressed.

7. The combination with a typewriter carriage of mechanism for supporting and raising it, a shift key lever connected therewith, 95 locking devices applied to the shift key lever for holding the carriage in raised position, a latch adapted to engage the carriage raising mechanism when the carriage is raised, a lever for actuating the locking devices, and connections between said lever 100 and the latch whereby the latch is moved to engage the carriage raising mechanism when the latter is raised.

8. The combination with a typewriter carriage of mechanism for supporting and raising it, a shift key lever for actuating the carriage raising mechanism, locking devices operating upon the shift key lever for holding 105 the carriage in raised position, a latch 110 adapted to engage the carriage raising mechanism when the carriage is raised, a locking lever for actuating the locking devices and for also actuating the shift key lever, and connections between said locking lever and the latch whereby the latch is moved to engage the carriage raising mechanism when the latter is raised.

In testimony whereof, I have hereunto subscribed my name.

EDWARD B. HESS.
